US00D910086S

(12) **United States Design Patent** (10) Patent No.: **US D910,086 S**
(45) Date of Patent: **** Feb. 9, 2021**

(54) **WORK MACHINE**(71) Applicant: **DEERE & COMPANY**, Moline, IL
(US)(72) Inventors: **Eric Keen**, Manhattan, KS (US); **Brian Huenink**, Cedar Grove, WI (US); **Richard N. Knowles**, Waterloo, IA (US); **Thomas C Boe**, Cedar Falls, IA (US); **Felix Nagelin**, Malibu, CA (US); **Thorsten Hagner**, Ilvesheim (DE); **Michael D Kollath**, Concordia, IA (US); **Charles N Warren**, Waterloo, IA (US); **Daniel J DeBoer**, Waucoma, IA (US); **William Clayton Martin**, Stillwater, OK (US); **John W. Krieger**, Westlake Village, CA (US); **Volker Durre**, Rancho Palos Verdes, CA (US); **Sebastian Himpel**, Mannheim (DE)(73) Assignee: **DEERE & COMPANY**, Moline, IL
(US)(***) Term: **15 Years**(21) Appl. No.: **29/671,770**(22) Filed: **Nov. 29, 2018**(30) **Foreign Application Priority Data**May 30, 2018 (EP) 005288503
May 30, 2018 (EP) ..... 005289014(51) **LOC (13) Cl.** ..... **12-09**(52) **U.S. Cl.**USPC ..... **D15/23; D15/33**(58) **Field of Classification Search**USPC D15/10, 11, 13-17, 28, 22-26, 30, 31,

CLAIM

The ornamental design for a work machine, as shown and described.

DESCRIPTION

FIG. 1 is a top, front, left perspective view of a work machine embodying our new design;

FIG. 2 is a left side elevational view thereof;

FIG. 3 is a right side elevational view thereof;

FIG. 4 is a front elevational view thereof;

FIG. 5 is a rear elevational view thereof;

FIG. 6 is a top plan view thereof; and,

FIG. 7 is a bottom plan view thereof.

The broken line representations in the figures show unclaimed environment or boundaries, and thus form no part of the claimed design.
